US0D1033135S

(12) **United States Design Patent** (10) **Patent No.:** **US D1,033,135 S**
(45) **Date of Patent:** **** Jul. 2, 2024**

(54) **FOOD PROCESSING ATTACHMENT**

(71) Applicant: **WHIRLPOOL CORPORATION**,
Benton Harbor, MI (US)

(72) Inventors: **Kaitlyn M. Benoit**, St. Joseph, MI (US); **Michael P. Conti**, St. Joseph, MI (US); **John Dykhouse**, Benton Harbor, MI (US); **Timothy J. Hicks**, Berrien Springs, MI (US); **Mitchell L. Robertson**, Elkhart, IN (US)

(73) Assignee: **WHIRLPOOL CORPORATION**,
Benton Harbor, MI (US)

(**) Term: **15 Years**

(21) Appl. No.: **29/916,655**

(22) Filed: **Nov. 14, 2023**

Related U.S. Application Data

(63) Continuation of application No. 29/892,912, filed on May 23, 2023, now Pat. No. Des. 1,011,833, which is

(57) **CLAIM**

The ornamental design for a food processing attachment, as shown and described.

DESCRIPTION

FIG. 1 is a front-right perspective view of a food processing attachment according to the design;

FIG. 2 is a back-right perspective view thereof;

FIG. 3 is a front-right perspective view thereof showing the food processing attachment mounted with an environmental food processing device; and,

FIG. 4 is a back-right perspective view thereof showing the food processing attachment mounted with the environmental food processing device.

The portions of the article shown in even broken line form no part of the claimed design.

(Continued)

Dash-dot-dash broken lines are environmental only and form no part of the claimed design.

1 Claim, 3 Drawing Sheets

Related U.S. Application Data

a continuation of application No. 29/813,549, filed on Oct. 29, 2021, now Pat. No. Des. 990,976, which is a continuation of application No. 29/732,296, filed on Apr. 23, 2020, now Pat. No. Des. 939,272, which is a continuation of application No. 14/983,735, filed on Dec. 30, 2015, now Pat. No. 10,820,735.
